UNITED STATES PATENT OFFICE.

EDGAR CHERRY, OF OAKLAND, CALIFORNIA.

SOUND-TRANSMITTING DEVICE.

1,296,763.

Specification of Letters Patent. Patented Mar. 11, 1919.

Application filed July 29, 1918. Serial No. 247,202.

To all whom it may concern:

Be it known that I, EDGAR CHERRY, a citizen of the United States, and a resident of Oakland, in the county of Alameda and State of California, have invented a new and Improved Sound-Transmitting Device, of which the following is a full, clear, and exact description.

This invention relates to a sound transmitting device of that kind adapted to be carried by a partially deaf person for enabling sounds to be heard.

The invention has for its general objects to improve the construction of devices of this character so as to be extremely sensitive to sounds and also adjustable as to sensitivity to suit the requirements of the user, this being brought about by having a diaphragm chamber of adjustable size.

Another object of the invention is the provision of an improved form of earpiece or receiver whereby the sounds can be better heard.

A still further object of the invention is the provision of a novel connection between the flexible tube and the transmitter.

With such objects in view, and others which will appear as the description proceeds, the invention comprises various novel features of construction and arrangement of parts which will be set forth with particularity in the following description and claim appended hereto.

In the accompanying drawing, which illustrates one embodiment of the invention and wherein similar characters of reference indicate corresponding parts in all the views.

Figure 1 is a perspective view of the sound transmitting device;

Fig. 2 is a front view of the transmitter with the adjustable cap and diaphragm removed;

Fig. 3 is a diametrical section of the transmitter; and

Fig. 4 is a diametrical section of the earpiece or receiver.

Referring to the drawing, A designates the transmitter, B the flexible sound-conducting tube, and C the earpiece or receiver.

The transmitter A comprises a body 1 in the form of a circular piece provided with a chamber 2 and having a threaded opening 3 in its back. The circumference of the annular body 1 is formed with a screw-thread 4 and a peripheral flange 5. Engag-

ing the thread 4 is a cap 6 provided with a large opening 7 or equivalent means for admitting sound vibrations to the interior of the transmitter so as to act on the diaphragm 8, which is fastened at one point near its periphery to a bearing block 9 arranged in the body 1, the periphery of the diaphragm being free at all points except where it is attached to its support. The front chamber or space 10 to the open side of the diaphragm 8 is adjustable in size by screwing the cap 6 further on or off the body 1. The cap 6 is adapted to be held in adjusted position by a set-screw 11. In turning the cap the flange 5 is engaged by one end and the cap 6 by the other, and then by relative turning movement the cap is screwed back or forth.

An attaching coupling 12 has a nipple 13 to which is applied the tube B. The coupling 12 has a peripheral flange 14 which is adapted to grip when screwing the coupling in or out. The coupling has a bore 15 which flares on a wide angle toward the diaphragm so that the sound waves from the diaphragm will be concentrated and conducted into the tube B.

The receiver or earpiece C is preferably, although not necessarily, a flexible rubber hollow hemispherical member 16 attached to the tube B, the latter having an extremity 17 extending into the member 16. This extremity 17 is flexible and is adapted to be placed at the end of the ear passage, and in the edge are notches 18, which provide for air circulation and a better passage of sounds. The extremity 17 terminates short of the edge of the trumpet-like member 16 so that the edge 19 of the latter can bear against the outer ear while the tubular member 17 is in proper relation to the sound passage of the ear.

A sound transmitting device of the character shown possesses great sensitiveness and a wide range of adjustment as to sensitiveness. It is comparatively simple and inexpensive to manufacture, and the flexible or soft rubber receiver enables a better application of the device to the ear and allows the device as a whole to be packed into a comparatively small space when not in use.

From the foregoing description taken in connection with the accompanying drawing, the advantages of the construction and method of operation will be readily understood by those skilled in the art to which the

invention appertains, and while I have described the principle of operation, together with the device which I now consider to be the best embodiment thereof, I desire to have it understood that the device shown is merely illustrative and that such changes may be made when desired as fall within the scope of the appended claim.

Having thus described my invention, I claim as new and desire to secure by Letters Patent:

A sound transmitting device of the character described, comprising a body having a threaded opening in its back and a threaded periphery, the front of the body having a

chamber formed in two diameters, a diaphragm secured at one point to the body to lie within the portion of the chamber having the larger diameter, an apertured cap screwing on the body, an externally threaded coupling member screwing into the threaded opening of the body, said member having a bore whose inner end is flared and provided with a nipple on its outer face, a flexible tube having one end secured on the nipple, and a hemispherical ear piece secured to the other end of the tube with the end of the tube extending into the same. 20 25

EDGAR CHERRY.
